UNITED STATES PATENT OFFICE.

JOHN F. STANDISH, OF WINTHROP, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ART OF HEELING SHOES.

1,288,253.

Specification of Letters Patent. Patented Dec. 17, 1918.

Application filed April 19, 1916. Serial No. 92,143.

To all whom it may concern:

Be it known that I, JOHN F. STANDISH, a citizen of the United States, residing at Winthrop, in the county of Essex and State 5 of Massachusetts, have invented certain Improvements in the Art of Heeling Shoes, of which the following description, in connection with the accompanying drawings, is a specification, like reference characters on 10 the drawings indicating like parts in the several figures.

This invention relates to methods of attaching heels to boots and shoes and more particularly to methods of attaching heels 15 comprising a leather and a rubber section.

It is an object of the present invention to provide a method whereby the complete heel may be attached at a single operation, as distinguished from the methods heretofore practised in accordance with which the 20 leather section and the rubber section have been attached in successive operations by separate gangs of attaching nails. My co-pending application Serial No. 53,948, filed 25 October 4, 1915, discloses a machine intended for attaching such heels in that manner.

By the method of the present invention I have succeeded in eliminating one of the nail driving operations heretofore necessary, thus reducing the expense of attaching 30 heels of this class, and at the same time greatly simplifying the mechanism necessary for attaching such heels. Moreover, the practice of my novel method improves 35 the accuracy with which the heel sections are located upon the shoe and subjects the rubber section to less detrimental usage than formerly. The quality of the work and the condition of the rubber are therefore improved and the life of the heel lengthened. 40

In one of its aspects my novel method is characterized by first permanently securing together the rubber and leather sections of the heel and then attaching the heel so 45 formed to the sole of the shoe to be heeled.

The manner of securing together the leather and rubber sections is not of particular moment. As herein shown they are cemented together while each section is held 50 against angular displacement by a suitable holder. In this manner accurate location of the sections is secured and a permanent and satisfactory bond is formed.

It is desirable in driving attaching nails

into a rubber heel section neither to subject 55 the rubber section to an excessive pressure nor to cut the material of the section by forcing drivers into it, as such treatment impairs the shape and consistency of the rubber. Accordingly, in practising my 60 novel method, the pressure necessary to insure a close union between the heel and the shoe sole is secured by pressure applied to the leather section while the rubber section remains substantially uncompressed. As 65 herein shown the desired results are secured by building a sectional heel having a shoulder formed by a portion of the leather section, pressing the heel against the shoe sole by pressure on this shoulder, and driving the 70 attaching nails while the heel is so held.

Another characteristic step of the method of the present invention consists in holding the completed heel in predetermined relation to the drivers by a holder similar in 75 shape to that used in holding the rubber section during the step of assembling and uniting the two heel sections. This procedure insures an accurate alinement of the embedded washers and the drivers and also the 80 correct disposition of the attaching nails in the leather section.

Other features of the novel method of this invention will be apparent from a consideration of the following description in 85 connection with the accompanying drawings illustrating the preferred manner of practising the method, in which,—

Figure 1 is a view in perspective of a rubber heel section in process of having a 90 coating of cement applied thereto;

Fig. 2 is a similar view of a leather heel section;

Fig. 3 is a view in perspective, partly in section, showing the heel building apparatus 95 and a completed heel in position therein;

Fig. 4 is a view of portions of a heel attaching machine suitable for carrying out certain steps of the method, and

Fig. 5 is a view in perspective, partly in 100 section, of an attached heel held by the holder of the heel attaching machine.

The rubber heel section 8 herein disclosed is molded in substantially the shape it is to present in the finished shoe. It is provided 105 with a series of embedded conical washers 10 arranged in a horseshoe-shaped design in registration with nail passages 12 extending

inwardly from the tread surface of the heel to the washers. A rubber heel section of this description constitutes the subject-matter of my co-pending application Serial No. 5 3173, filed January 19, 1915, to which reference may be had for a detailed description thereof. Each conical washer 10 serves to deflect into its opening the point of an attaching nail, thus insuring the passage of 10 the nail through the washer, while the washer as a whole affords firm holding for the nail in the heel section when the head of the latter is driven to the surface of the washer. As indicated in Fig. 1 the first 15 step of the method consists in coating the upper surface of the rubber section 8 with cement, as for example rubber cement 14. This may be applied by means of a brush 16 or in any other suitable manner.

20 The leather heel section 18 is shown in inverted position in Fig. 2. This section is of appreciably larger dimension than the rubber section and is intended to be reduced to the desired size by trimming after the 25 attaching operation. The second step of the present method consists in applying cement 14 to the outer surface of the leather section. This may be done with the brush 16 as before.

30 The next step of the method consists in permanently securing together the leather section 18 and the rubber section 8 in that relation which they are to occupy in the finished shoe. This may be effected by 35 bringing the two cemented and partially dried surfaces into engagement and pressing the surfaces together.

It is desirable that when the sections of 40 the heel are first brought into contact they should occupy the desired relative positions for the nature of the cement renders it difficult to vary or correct the relationship of the two sections after contact is made. In Fig. 3 there is shown one form of apparatus 45 which may be employed to good advantage in carrying out this step. This apparatus comprises a bottom plate 20 having an aperture 22 shaped to receive one of the rubber sections 8. Preferably the plate is provided 50 with a series of apertures of various sizes so that rubber sections of different sizes may be accommodated. An upper plate 24, provided with apertures 26, shaped to receive the leather sections 18 is secured in place 55 above the plate 20. The plate 20 is of slightly less thickness than the rubber sections so that when one of these sections is placed in an aperture 22 with its outer surface down, its upper cemented surface will 60 project slightly above the upper surface of the plate 20. The upper plate 22 need be of sufficient thickness only to engage the margin of a leather section 18 and hold it in the proper relation to the rubber section beneath it. When the illustrated apparatus is

used the leather section is presented in the aperture 26 with its cemented face down. A permanent union is secured between the two sections of the heel by applying pressure to the heel seat surface of the leather section 18, the two sections being thereupon permanently united by the rubber cement. The marginal portions of the leather section 18 will ordinarily be maintained out of contact with the upper surface of the plate 20 by the slightly thicker rubber section 8 but if such contact should occur no substantial bond will be established between the cemented surface of the leather section and the uncemented surface of the metal plate. 75 80

Having constructed the heel as above outlined it is removed from the heel building apparatus and is ready for attachment to the shoe sole. In this operation the leather section 18 is pressed against the sole of a 85 shoe with sufficient force to insure a perfect union in the nail driving operation by pressure upon the marginal shoulder 19 formed at the base of the rubber section 8. The rubber section 8 meanwhile is maintained substantially uncompressed and while the heel is held in this condition headed attaching nails are driven into the passages 90 12 until their heads are seated against the washers 10. 95

Figs. 4 and 5 illustrate sufficient of the construction of a heel attaching machine suitable for carrying out the attaching step of the method to convey a clear understanding thereof. This machine is disclosed in 100 full detail in United States Patent No. 1,207,563, granted on an application of H. W. Kenway, to which reference may be had for features not herein illustrated. This machine is provided with a stationary die 105 plate 30 provided with nail receiving passages for the attaching nails and with a jack 32 upon which the shoe to be heeled is supported. Beneath the die plate 30 are provided ways for an apertured heel holding plate 34. The aperture in plate 34, as shown in Fig. 5, corresponds exactly in shape to the aperture 22 of the plate 20 in the heel building apparatus so that when a completed heel is presented its rubber section 8 completely fills the aperture and the heel is retained in position beneath the die plate. The thickness of the plate 34 is substantially equal to that of the rubber section 8 so that the lower surface of the plate 34 will rest 110 upon the ledge or shoulder formed by the upper marginal surface of the leather section 18. In some cases it may be desirable to employ a plate 34 of slightly less thickness than the rubber section 8 and in such 115 case the rubber section will be slightly compressed and forced evenly against the cemented surface of the leather section 18. The amount of pressure thus developed, however, is relatively slight and will not pro- 120 125 130

duce substantial deformation of the rubber section in any case.

The machine frame 36 is provided with vertical bearings for side rods 38 carrying 5 a cross head 40 having a gang of drivers 42 mounted thereon and arranged in alinement with the nail receiving passages. The jack 32 is carried by a vertically movable jack carriage 44 resting on a block 46 and ar- 10 ranged to be elevated vertically by the action of a pair of cams 48 oscillated by the power of the machine during the initial movement of the cross head.

When the machine herein shown is em- 15 ployed for carrying out the present step of the method, the heel is placed in the apertured holder plate 34 as shown in Fig. 5 and the shoe is placed upon the jack 32 with its sole 28 uppermost. The jack is then ele- 20 vated into preliminary engagement with the heel seat surface of the leather section 18 of the heel and the machine thereupon started. The cams 48 then act to elevate the jack and the leather section 18 is firmly 25 pressed, by pressure upon its marginal portion, against the shoe sole. While the leather section 18 is so held under pressure and the rubber section remains substantially uncom- 30 pressed, the cross head 40 continues to de- 35 scend and the attaching nails 11 are driven downwardly from the nail receiving pas- 40 sages in the die plate 30, being followed by the drivers until their heads are seated upon the upper surfaces of the washers 10. The 45 attaching nails pass through the sole 28 and are clenched inside the shoe thus attaching the completed heel firmly in place. The 50 cross head is then lifted and the jack lowered with the heeled shoe, drawing the rubber section 8 out of the aperture in the plate 34 and leaving the machine in readiness for operating upon the next shoe.

It will be apparent that the machine herein described is in no way essential to the 45 practice of the method of my invention, but that any heel attaching machine, equipped to hold the heel in the manner above outlined and to drive the attaching nails while the heel is so held, might equally well be 50 employed.

Having thus described my novel method and preferred apparatus for carrying it into effect, what I claim and desire to secure by Letters Patent of the United States is:

55 1. That improvement in the art of heel- ing shoes which comprises permanently se- 60 curing together in superposed relation a leather and a rubber heel section, and then attaching the heel so formed to the sole of a shoe while the rubber section is confined against lateral expansion.

65 2. That improvement in the art of heel- ing shoes which comprises permanently se- 70 curing together a leather and a rubber heel section, and then driving a gang of headed

attaching nails through the heel and shoe sole, embedding the heads of the nails in the rubber section while said section is confined about its margin, thereby attaching the heel to the shoe. 70

3. That improvement in the art of heel- 75 ing shoes which comprises cementing together a leather heel section and a smaller rubber heel section, pressing the leather heel sec- 80 tion against a shoe sole by pressure on its portions which project beyond the rubber section, and driving a gang of headed at- 85 taching nails through the heel and below the surface of the rubber section.

4. That improvement in the art of heel- 85 ing shoes which comprises uniting leather 90 and rubber heel sections in symmetrical superposed relation while holding the sec- 95 tions against angular displacement, pressing the leather section against a shoe sole while the rubber section is substantially uncom- 100 pressed, and driving a gang of attaching nails through both sections.

5. That improvement in the art of heel- 95 ing shoes which comprises placing in a form a rubber heel section of greater height than the portion of the mold which engages the rubber section, said section being coated on one surface with cement, bringing a leather 105 heel section, coated on its proximate face with cement, into permanent engagement with the rubber section while the leather section is held in predetermined angular position, and finally driving attaching nails through both sections. 100

6. That improvement in the art of heel- 110 ing shoes which comprises placing in an apertured holder a rubber heel section bearing spaced washers embedded therein, at- 115 taching a leather heel section to the rubber section, inverting the heel so formed, lo- 120 cating the heel with respect to nail passages by placing the rubber section of the heel in an apertured holder similar to that first mentioned, and driving attaching nails through the washers of the rubber section. 110

7. That improvement in the art of heel- 125 ing shoes which comprises building in an apertured holder a heel having a rubber sec- 130 tion with embedded washers, locating the heel with respect to nail passages by insert- 135 ing a portion thereof in an apertured holder similar to that first mentioned, and driving attaching nails through the washers while the heel is held by the latter holder. 120

8. That improvement in the art of heel- 140 ing shoes which comprises building a sectional heel having a shoulder with a surface par- 145 allel to that of its tread face, pressing the heel against a shoe sole by pressure on the shoul- 150 der, and driving attaching nails through both sections of the heel. 125

9. That improvement in the art of heel- 155 ing shoes which comprises building a heel having a leather base and a rubber tread 160

section, the leather base forming a shoulder with a face parallel to that of the tread face of the heel, applying pressure upon the shoulder at the ends of the heel to force the leather base against a shoe sole, and inserting attaching nails while the pressure is maintained.

10. That improvement in the art of heel-
ing shoes which comprises locating a leather
10 heel section symmetrically with respect to
washers embedded in a rubber section by

securing the sections together while held by rigid forms, locating the leather heel section in the same relation to a gang of drivers by inserting the rubber section of the complete heel in a similar rigid form located properly with respect to the drivers, and driving the attaching nails while the heel is so held.

15 In testimony whereof I have signed my name to this specification.

JOHN F. STANDISH.
